UNITED STATES PATENT OFFICE.

SILAS M. FORD, OF ST. PAUL, MINNESOTA.

LATH-BOARD.

1,194,003.

Specification of Letters Patent. Patented Aug. 8, 1916.

Application filed March 24, 1916. Serial No. 86,411.

To all whom it may concern:

Be it known that I, SILAS M. FORD, a citizen of the United States, residing at St. Paul, in the county of Ramsey and State of Minnesota, have invented certain new and useful Improvements in Lath-Board, of which the following is a specification.

My invention relates to improvements in lath-board of waterproofed paper or other flexible sheeting corrugated to form lath like projections and intermediate depressions or valleys, and designed to be fastened to the studding or beams of buildings to serve as a foundation for plaster, so that the depressions or valleys on the underside of the board will form dead air spaces while the valleys on its plastering face will form plaster receiving spaces. It is desirable to make the board in large sheets which can be rolled or packed for shipping and afterward cut to the size and shape desired in use.

It is the object of the invention to provide improved means for bracing and protecting the corrugations from being crushed or flattened in handling and use, and also for binding them together so that they will not spread apart, with the consequent impairment of their capacity as dead air spaces or plaster receiving spaces.

With these objects in view I have provided strips arranged transversely of the board and carrying at intervals prongs which project down through the board portions at the bottom of the valleys and are formed with lateral shoulders which bear against the upper faces of said board portions so as to form strut-like supports. The struts are preferably positioned so as to resist the lateral thrust of the projections when the same are under pressure.

More particularly the invention consists in the construction, combination, and arrangement of parts hereinafter described and claimed.

In the accompanying drawings forming part of this specification, Figure 1 is a perspective view of a fragment of lath-board embodying the present invention; Fig. 2 is an end view of the same; Fig. 3 is an end view of a fragment of the same shown provided with a backing sheet; and Fig. 4 is a perspective view of a binding strip embodying the invention.

The lath-board which is the subject of this invention is made of flexible sheeting,

preferably waterproofed paper, pressed or molded to form corrugations or alternate projections and depressions or valleys, so that the projections on one side will form the valleys on the other and vice versa. The corrugations are preferably of plait-like keyed-lath shape, that is of the shape of a lath having keyed or inwardly extending sides, as shown in the drawings, where 2—2 represent the lath projections on the outer face of the board, and 3—3 the valleys or depressions between them. These depressions are formed by stamping out the lath projections 4 on the inner face of the board, and there are similar depressions or valleys 5 between the lath projections 4, these valleys being formed by stamping up the projections 2. The valleys or longitudinal channels 3 which are open on the outer or plastering face of the board serve as plaster receiving spaces, while the oppositely facing valleys or channels 5 under the hollow stamped up lath projections 2 serve as dead air heat insulating and sound deadening spaces.

To brace and protect the corrugations from becoming crushed or spread apart in handling and use, I have provided sheet metal strips 6 which are arranged transversely of the corrugations and preferably extend across the face of the same at suitable intervals apart. These strips are secured to the board by means of struts 7 which project down through the bottom portions of the board and are formed with lateral shoulders or knees 8 in position to abut or bear against the upper faces of said bottom board portions. Below the shoulders the struts terminate in prongs 9 which pierce and extend through the bottom portions of the board and are bent or clenched over against the under side of the same. The struts are preferably integral or fast with the binding strips 6 and stamped out of the strips themselves, as shown in the drawings. They are also preferably formed with lateral arms 10 bent up at the shoulders so as to bear against the upper face of the bottom board portion. Where the corrugated board is formed with a backing sheet on the underside, as shown at 11 in Fig. 3, the prongs of the struts may extend through this sheet and be bent over or clenched upon the under side of the same.

It will be evident that when a weight is

laid, or pressure is exerted, upon the strips, the thrust will be received and resisted by the struts, which will thus relieve the projections and folds of the board from pressure, and prevent them from being crushed, while the struts, when they confine the projections at the sides, as would usually be the case when they are of keyed lath shape, will offer lateral resistance to any flattening pressure exerted upon the face of the board whether the same comes directly upon the strips or upon the portion of the projections between the strips.

I claim:

- 15 1. A lath-board comprising a sheet of flexible material corrugated to form inter-spaced lath projections and intermediate depressions, strips arranged transversely of the projections, and struts securing the strips to the board at intervals, said struts extending down through the bottom portions of the board and being formed with lateral shoulders in position to bear against the upper face of said bottom board portion whereby to form struts between said strips and said board portions.
- 20 2. A lath-board comprising a sheet of flexible material corrugated to form keyed-lath shaped projections and intermediate depressions, strips arranged transversely of the projections, and struts securing the strips to the board at intervals, said struts extending down at the side edges of the projections and through the board portions at the bottom of the depressions, and being formed with lateral shoulders in position to

bear against the upper faces of said bottom board portions.

3. A lath-board comprising a sheet of flexible material corrugated to form inter-spaced lath projections and intermediate depressions, sheet metal strips supported upon, and extending transversely across, the faces of the projections, and struts carried by the strips at intervals, said struts extending down into the depressions and through the board portions at the bottoms thereof, said struts being formed intermediate their length with lateral shoulders in position to bear against the upper faces of said bottom board portions.

4. A lath-board comprising a sheet of flexible material corrugated to form keyed-lath shaped projections and intermediate depressions, said projections having inwardly inclined sides, sheet metal strips supported upon, and extending transversely across, the faces of the projections, and struts carried by the strips at intervals, said struts extending down adjacent the side edges of the projections into the depressions between them and through the board portions at the bottom of the depressions, said struts being formed with lateral shoulders in position to bear against the upper faces of said bottom board portions.

In testimony whereof I affix my signature in presence of two witnesses.

SILAS M. FORD.
